CLAIM

The ornamental design for a back plate for a thermostat device as shown and described.

DESCRIPTION

FIG. 1 is a perspective view of the back plate for a thermostat device.

FIG. 2 is a front elevation view of the back plate for a thermostat device.

FIG. 3 is a rear elevation view of the back plate for a thermostat device.

FIG. 4 is a top plan view of the back plate for a thermostat device.

FIG. 5 is a bottom plan view of the back plate for a thermostat device.

FIG. 6 is a left side elevation view of the back plate for a thermostat device; and,

FIG. 7 is a right side elevation view of the back plate for a thermostat device.

1 Claim, 3 Drawing Sheets
